TRAVELLING WAVE MAGNETRONS

Robert Gibson Robertshaw, Wembley, and William Ernest Willshaw, Kenton, England, assignors to The M-O Valve Company Limited, London, England

Application March 24, 1955, Serial No. 496,549

Claims priority, application Great Britain March 25, 1954

15 Claims. (Cl. 315—39.3)

This invention relates to travelling wave magnetron oscillator devices of the kind having an anode structure defining an even plurality of cavity resonators spaced round, and opening on to, a cylindrical electron orbit space within which is located the cathode of the magnetron.

Such devices are arranged to co-operate with means for producing a magnetic field directed parallel to the axis of the electron orbit space, which field, in conjunction with a radial electrostatic field applied between the cathode and the anode, causes the electrons emitted from the cathode to flow round the cathode and excite the cavity resonators; the oscillating electric fields set up between the cavity resonators in the electron orbit space cause the electrons to become "focussed" or "bunched" into spoke-like regions which travel round the cathode in synchronism with a component of the electric field set up by the resonators, so that there is a continual transfer of energy from the electrons to the electric field.

Such devices have the advantage that they can be designed to produce oscillations of short wavelengths, for example 10 centimetres, at relatively high power and with relatively high efficiencies as compared with the conventional grid-controlled thermionic valve oscillators, and can also be designed to operate with reasonable efficiency at much shorter wavelengths, for example 3 centimetres or less, which are outside the range of operation of the conventional thermionic valve oscillators.

The travelling wave magnetron devices also compare favourably with other forms of electronic oscillators, for example velocity modulated klystrons, in respect of efficiency at these very short wavelengths, but for continuous wave operation at low powers, with low anode/cathode voltages and magnetic fields as used, for example, in radio receivers or portable transmitters, the mechanical difficulties of making the devices for operation at wavelengths of much less than 3 cms. increase rapidly with decreasing wavelength since the dimensions of the device, and in particular of the anode structure, become very small and the permissible tolerances in manufacture also decrease.

It has been proposed to reduce this difficulty by causing a magnetron of the type specified to operate on a space-harmonic of its fundamental π -mode frequency, and in order that the present invention may be fully understood, the nature of this proposal will be explained in more detail.

Magnetrons of the type specified are capable of operating in different modes of oscillation of the anode system which are characterised by different values of the instantaneous phase difference between the electric fields in adjacent resonators. Thus if there are N resonators the phase difference between adjacent resonators may assume any one of the values $2\pi n/N$ radians, where n is one of the integers 0, 1, 2 . . . $N/2$. A value of n equal to $N/2$ corresponds to oscillation of the anode system in the so-called π -mode, the phase difference be-

2

tween adjacent resonators then being π radians, and this is the most usual mode for operation of magnetrons of the type specified.

The effect of the oscillating electric fields in the resonators is to impose potential variations between the adjacent anode segments between the resonators and these potential variations may be regarded as a series of potential waves travelling round the anode in either direction with angular velocity $2\pi c/\lambda n$ radians per second, where λ is the free space wavelength of the electrical oscillations in the resonators of the anode system, c is the velocity of the electrical oscillations in free space, and the value of n corresponds to the particular mode in which the resonators of the system are oscillating.

15 An electron travelling round the anode with angular velocity $2\pi c/\lambda n$ in the same direction as one of said waves in such phase as to transfer energy thereto will thus be maintained in synchronism with the wave and will continually transfer energy thereto. However it can be shown that electrons of certain other angular velocities will also be maintained in synchronism with the wave, and if the wave, which is non-sinusoidal, be regarded as formed by a series of Fourier components, these electron velocities correspond to particular ones of these components, which particular ones will hereinafter be referred to as space harmonics.

Thus if the wavelength of the electrical oscillations is λ , the space harmonics are those components which effectively travel round the anode system with angular velocity $2\pi c/\lambda k$, where k (defined hereby) is an integer which is different for different space harmonics.

For the normal symmetrical arrangement of resonators, $k=n+pN$ and $p=0, \pm 1, \pm 2$ etc. For the purposes of this specification only positive values of p need be considered. The first value in the series corresponds, of course, to the fundamental oscillation. It will later be pointed out that with an unsymmetrical arrangement k may have other values in addition to those indicated by the above formula.

40 It will therefore be seen that it is in theory possible to operate a symmetrical magnetron of the type specified in any particular mode, corresponding to a particular value of n , under any one of a number of different conditions giving different electron velocities round the cathode.

45 The manner in which this possibility might simplify the aforesaid difficulty of designing magnetrons of the type specified for operation at high frequency will now be indicated.

Thus the operating conditions of such a magnetron may be expressed to a first degree of approximation by the formula

$$V = \frac{0.948}{\lambda k} r_a^2 B \left[1 - \left(\frac{r_c}{r_a} \right)^2 \right] \quad (1)$$

55 where

V is the electrostatic voltage applied between anode and cathode, in kilovolts,

B is the magnetic field in gauss

r_a is the radius of the anode in centimetres

r_c is the radius of the cathode in centimetres, and

λ and k are as before.

60 The wavelength λ of the electrical oscillations is, for operation in a particular mode, such as the π -mode, and ignoring frequency changes which might result from the loading of the device, determined by the dimensions of the cavity resonators. Thus if, starting with a given design for which condition (1) is fulfilled, the resonators are modified to decrease λ , then for the new design one or a combination of the following further modifications will need to be made in order that condition (1) may

still be satisfied and oscillation of the modified device obtained:

- (a) V increased or B decreased
- (b) r_a reduced or r_c increased
- (c) k increased

Now usually it is undesirable or impracticable to alter appreciably V or B for continuous wave low power operation; (b) involves reducing the dimensions of the anode system, which gives rise to the difficulties aforesaid, or increasing the cathode diameter, which is undesirable, and it would appear that these difficulties might be avoided by means of (c).

One method of increasing k is by increasing the number N of resonators in the anode system; by this means the desired operating wavelength can in some cases be secured without undue alteration of r_a and r_c and without undue increase of V or reduction of B , but further mechanical difficulties then arise, at very short wavelengths, in forming the resonators with the required accuracy, especially in view of the short gap width at the electron orbit space which is imposed by the larger number of resonators.

An alternative method of increasing the value of k is by increasing the value of p , that is to say, causing the magnetron to operate on one of the space harmonics of the anode potential wave, but this method does not appear to have been successfully adopted hitherto.

We believe that this has been due to the fact that the design of the known magnetrons with which operation on a space harmonic has been attempted has not been suitable for this purpose, and in particular the amplitude of the space harmonic of the anode potential wave with which interaction has been sought has, because of the way in which the device was constructed, usually been too small to permit such interaction. The main object of the present invention is to provide a form of magnetron of the type specified which is more suitable for operation on a space harmonic in continuous wave operation at relatively low power. It will, however, be appreciated that valves in accordance with the invention can also be used for pulse operation and may in some cases be designed specifically for such use.

The foregoing explanation has, for simplicity, been based on the assumption that the anode resonators are symmetrically arranged around the cathode; such a symmetrical arrangement is not, however, essential for the construction of a magnetron in accordance with the invention and before stating the invention formally the more general arrangement of resonators possible in accordance with it will first be defined.

The operation of an N -segment magnetron on a space harmonic corresponds, as regards the number of effective antinodes in the instantaneous anode potential wave, with the fundamental π -mode operation of an anode system having $2k$ resonators, where the value of k is related to N and depends on the particular harmonic considered, as aforesaid. Now imagine in a magnetron having N resonators, the circumference of the electron orbit space divided by $2k$ equally spaced points. Then with a symmetrical arrangement of the resonators, the centres of the gaps at which the resonators open on to the electron orbit space will each coincide with one of said points, which may be called a resonator point, and these resonator points will include between each other the same number of other points.

The more general arrangement of the resonators possible in magnetrons in accordance with the invention is as follows: The N resonators are arranged in $N/2$ pairs with each resonator centred on a resonator point as aforesaid, with the two resonator points of each pair including between them an even number, which may be zero, of the remainder of said points, and with an even number, which is not zero, of said points included between the adjacent resonator points in different pairs, the same number of points being included between each

pair. For example in a 6 resonator system operating on the harmonic for which k is 12, there are 24 of said points and the resonators may be centred on the 1st, 4th, 9th, 12th, 17th, and 20th points, starting at any one of the points. The possible positions of the resonators corresponding to this more general arrangement together with the symmetrical arrangement will hereinafter be referred to as the harmonic positions.

It may be noted that with unsymmetrical harmonic positions a greater number of space harmonics are available for interaction than with a symmetrical arrangement. Thus with π -mode operation of N resonators arranged non-symmetrically in $N/2$ pairs as aforesaid, interaction may be obtained with space harmonics corresponding to values of k equal to $pN/2$, where p is any integer, whereas in the symmetrical case the space harmonics with which interaction can be obtained are those given by $k=N(p+1/2)$. In each series the first value corresponds, of course, to the fundamental oscillation.

For example, if $N=6$, then with the general arrangement aforesaid the possible values of k are $3, p$, that is to say, $3, 6, 9, 12 \dots$ etc.

On the other hand with the symmetrical arrangement, again for $N=6$, the possible values of k are $6(p+1/2)$, that is to say, $3, 9, 15 \dots$ etc.

The invention can now be stated.

According to the invention a travelling wave magnetron oscillator of the type specified has an anode substantially in the form of a metal plate pierced perpendicular to its major faces by an aperture whose perimeter provides a cylindrical inner hole which forms the electron orbit space, the diameter of this space being not greater than $\lambda/4$ and the axial length of the space being not greater than $3\lambda/10$; the perimeter of said aperture also provides an even plurality N , not exceeding six, of spaces which form similar cavity resonators extending radially from the electron orbit space and spaced round its axis in harmonic positions as hereinbefore defined; a cylindrical cathode is mounted within the electron orbit space so as to lie accurately coaxial therewith; the anode and cathode structures are mounted within a sealed evacuated envelope which is such that oscillatory energy from the anode system can be radiated directly through the envelope; leads to the anode and cathode are sealed through the envelope; and the arrangement is such that in conjunction with a suitable magnetic field and anode/cathode voltage the device can oscillate at wavelength λ in the π -mode of the anode resonator system on a space harmonic of the anode potential wave corresponding to a value of k as hereinbefore defined equal to $Np/2$, where p is a small finite integer.

Preferably the diameter of the electron orbit space is not greater than $\lambda/10$ and the axial length of the space is also not greater than $\lambda/10$.

The ratio of cathode diameter to the diameter of the electron orbit space is not very critical in a valve in accordance with the invention, but with a valve designed specifically for continuous wave operation the value of the ratio is preferably arranged to be less than that normally used hitherto in comparable known valves, and a value of about 0.3 for the ratio is suitable. For valves in accordance with the invention designed for pulse operation the ratio may be about the same as that normally used hitherto, that is to say about 0.6.

Preferably the angular circumferential width of the gaps where the resonators open on to the electron orbit space is not less than $\pi/2k$ radians. It may be noted that the theoretically maximum possible gap width obtainable in the $2k$ -resonator magnetron, assuming infinitely thin anode segments, is π/k radians; the gap width in a magnetron in accordance with the invention may, however, be appreciably greater than that for the $2k$ -resonator magnetron, which has the advantage of enabling the amplitude of the desired space harmonic of

the anode potential wave to be increased relatively to interfering components, thereby facilitating excitation of this space harmonic. However, for certain values of the gap width, the amplitude of a space harmonic may be zero; thus the amplitude of the space harmonic k is zero for values of θ equal to $360^\circ/k$, where θ is the angle subtended by the gap at the axis of the electron orbit space, and these identical values must be avoided as far as the wanted space harmonic is concerned. On the other hand, use may in some cases be made of this property by arranging the gap width to correspond to the critical value of an unwanted space harmonic, and thereby preventing excitation of that harmonic.

These last mentioned properties depend on the anode potential wave round the anode surface being of the nature of a step-function, that is to say zero along the surfaces of the anode segments and rising infinitely steeply at the edges of the resonator gaps. In practice there is invariably some rounding of the edges of the resonator gaps; now one of the advantages of a magnetron in accordance with the invention, resulting from the simple resonator system and relatively wide gaps, is that the anode can often be formed by the relatively simple hot extrusion pressing process known in the art as hobbing, which in some cases may accentuate the rounding of the gap edges. To minimise this effect the sides of a resonator slot may be inclined away from the perpendicular to the chordal plane at which the slot intersects the electron orbit space, so as effectively to sharpen the edges of the gap formed by the intersection, this angle of inclination preferably lying between zero and $(90 - \phi)$, where ϕ is angle between the chordal plane and the tangent plane at the edge of the gap. It will be appreciated that for practical reasons of convenience in manufacture, such inclination of the sides of the slot may start slightly away from the mouth of the slot. This inclination of the sides also has the effect of increasing the L/C ratio for the resonators and with it the strength of the electric field at the resonator gaps, and hence the valve efficiency.

With a magnetron in accordance with the invention, especially when the N resonators are arranged symmetrically around the axis of the electron orbit space, as is preferred, we have found that stable operation on a space harmonic of the π -mode can readily be obtained. We believe that the reason for this is that the limitation of the number of resonators to less than 6 reduces the number of possible interfering modes and their components in the anode potential wave, and the dimensional limitations stipulated ensure the presence of relatively strong space harmonics in the anode potential wave, as well as minimising the occurrence of interfering components. The provision for the output of the magnetron to be radiated directly through the envelope avoids the necessity for an output coupling loop within one of the cavity resonators and prevents disturbances arising from that cause; however, in connection with this last mentioned point it may be possible and advantageous in some cases to provide a short probe projecting perpendicular to the anode plate from one of the anode segments for increasing the coupling of the anode system to a waveguide in one direction; usually, however, such a probe will not be necessary and is then preferably not used in order to minimise the disturbances introduced into the anode system. Thus preferably at least one of the cavity resonators extends so close to an edge of the plate that said edge part of the plate constitutes in effect an output loop the electromagnetic field linked with which in operation of the device extends to the exterior of the envelope.

Preferably the anode and cathode structures are arranged within a closely fitting cylindrical glass envelope dimensioned to fit snugly within a waveguide adapted to transmit oscillations of the output frequency of the magnetron, and for blocking the passage of high frequency energy in the reverse direction along the waveguide, the

anode plate is mounted at one end on a cylindrical metal sleeve which approaches closely and coaxially the inner surface of the glass envelope and is of axial length electrically equivalent to one quarter of a wavelength at the output frequency of the magnetron, so as to be capable of forming with the wall of the waveguide, when the device is inserted therein, a choke which presents a high impedance to the high frequency energy.

With the magnetron in accordance with the invention having six resonators, for which $N=6$ and $n=3$ for oscillation of the anode system in the π -mode, the permissible values of k for space harmonic operation are 9, 15, 21, etc., and preferably the magnetron is arranged to operate on the first space harmonic, corresponding to $k=9$.

With a magnetron in accordance with the invention having four resonators, for which $N=4$ and $n=2$ for oscillation of the anode system in the π -mode, the permissible values of k for space harmonic operation are 6, 10, 14 etc., and preferably the magnetron is arranged to operate on the first space harmonic, corresponding to $k=6$.

With a magnetron in accordance with the invention having two resonators, for which $N=2$ and $n=1$ for oscillation of the anode system in the π -mode, the permissible values of k for space harmonic operation are 3, 5, 7 and the magnetron is preferably arranged to operate on the second space harmonic, corresponding to $k=5$.

A particular advantage obtainable with a magnetron in accordance with the invention is that its simple anode structure renders it readily tunable over an appreciable frequency range by means of adjustable reactive loads without introducing such interfering components in the anode potential wave as to give rise to mode change troubles or appreciable loss of efficiency of operation on the desired space harmonic.

The invention will be further described with reference to the accompanying drawings, in which Figures 1, 2 and 3, illustrate two forms of magnetron in accordance with the invention, Figures 4, 5 and 6 indicate how magnetrons in accordance with the invention may be used, and Figures 7 and 8 illustrate modifications which may be incorporated in a magnetron in accordance with the invention.

One embodiment of the invention will now be described by way of example with reference to Figures 1 and 2 of the accompanying drawing, which show two side views of the magnetron taken at right angles to each other.

The magnetron comprises a cylindrical glass envelope 1 closed by a pressed glass base 2 which carries seven rigid terminal pins 3 on its outer side and through which are sealed electrical supply leads terminating in seven lead-in and electrode support wires 4 within the envelope.

The electrode system is mounted on these support wires and includes an anode in the form of a rectangular copper plate 5 screwed to the outer side of the base of a cylindrical copper choke cup 6 with an edge of the plate extending along a diameter of the base; the screws 7 which attach the anode 5 to the cup 6 pass also through holes in the cross-bar of a T-shaped nickel support member 8, the down stem of which lies along the axis of the cup 6 and is welded on each side to two of the support wires 4 so that the cup and anode are supported thereby substantially co-axially within the cylindrical envelope 1.

The anode plate 5 is pierced perpendicularly from the centre of one major face to the centre of the other by an aperture whose periphery provides a circular space 9 and four spaces 10 each in the form of a sector of a circle, the spaces 10 being symmetrically arranged around the space 9 so as to define between them four substantially rectangular anode segments 11 projecting along two mutually perpendicular diameters of a circular hole coaxial with the space 9, said diameters being each inclined at an angle of 45° to the axis of the choke cup 6. The electrode system also includes an indirectly heated cathode 12 supported accurately coaxial with and within the elec-

tron orbit space 9 between two mica cathode support sheets 13 each attached to a different one of the major faces of the anode plate 5.

Each mica sheet is provided near one edge with two holes into each of which is fixed a nickel eyelet 14, and each mica sheet is attached to the anode plate 5 by two copper-nickel pins 15 which pass through the nickel eyelets and through corresponding holes pierced through the anode plate adjacent to the choke cup 6, the mica plates being clamped to the plate by nickel retaining sleeves 16 fitted over the ends of the pins 15 and spot-welded to them; the mica sheets are spaced from the surfaces of the anode plate 5 by the heads 17 of the nickel eyelets 14.

At the region opposite the electron orbit space 9, each mica sheet 13 is pierced by four holes into which fit tags of a small, approximately rectangular, nickel cathode end shield 18, the latter each lying on the side of the mica nearer the anode plate and being held in position by the bending over of the tags on the other side of the mica.

The end shields 18 are coated with a material, such as titanium dioxide furnace in dry hydrogen to a fine black deposit, for increasing their thermal emissivity.

Each end shield 18 carries a central hole which lies opposite a hole pierced through the corresponding mica sheet, and through each of these further holes passes one end of the cathode 12, which consists of a hollow nickel tube coated with electron emissive material over the part of its outer surface within the electron orbit space 9 and carrying a heater 19 within the tube.

One end of the cathode 12 and the corresponding end of the heater 18 are connected to a lead wire 20 which passes, through a ceramic bushing 21 in the base of the cup 6, to one of the lead-in wires 4, and the other end of the heater is connected through a lead wire 22, which passes through a further ceramic bushing 23 in the base of the cup 2, to a different one of the lead-in wires 4. The lead wires 20 and 22 are each provided with a single turn loop for providing resilience and allowing for thermal expansion of the leads in use of the magnetron.

The envelope 1 is evacuated and sealed off at the end of the envelope opposite to the base 2, and is gettered by means of a getter element 24, which closes a wire loop carried by the remaining one of the lead-in wires 4, the loop being eddy current heated, after evacuation and sealing of the envelope, for dispersal of the getter.

The glass base 2 of the envelope is provided on its inside surface with a coating of magnesium oxide, applied in aqueous suspension and dried during the baking of the envelope during the processing of the device, for increasing the mutual insulation between the terminal pins.

The cathode support assembly is used for ensuring the accurate centering of the cathode during manufacture in the following manner:

The holes through the anode plate 5 into which the pins 15 fit are, when formed, accurately positioned relative to the axis of the electron orbit hole 9, and the pins 15 are an accurate fit within these holes, being staked and clenched into position using a circular tool. The plate 5 is mounted in a jig with the pins 15 in position in the anode plate and with a locating piece fitted into the electron orbit space 9, said locating piece having an axially cylindrical extension of the same diameter as the cathode tube which projects from one side of the plate; over this side of the anode plate is fitted the corresponding mica sheet 13 with the end plate 18 and nickel eyelets 14 fitted therein but not clenched to the mica; the central hole in the end plate 18 is fitted over the extension of the locating piece and the tags of the end plate turned down to hold it firmly in position on the mica; the nickel eyelets 14 are then pressed down to clench them firmly to the mica. The mica sheet is then withdrawn from the pins 15, the anode plate reversed in the jig, and the procedure repeated for the other mica sheet on the opposite side of the anode plate. The locating piece is then withdrawn

from the electron orbit hole, and replaced by the cathode, one end of which is inserted through the hole in the end plate of the mica sheet fitted to the anode plate, after which the second mica sheet is fitted to the anode plate, over the pins 15, so that the other end of the cathode passes through the central hole in the end plate carried by this second mica sheet. The two mica sheets are then fixed in position by spot-welding the nickel retaining sleeves 16 on to the projecting ends of the pins 15.

The anode-cathode assembly is thereafter secured to the choke cup 6 and supporting strip 8, which is in turn mounted on its support wire 4, and the cathode and heater connections to the leads 20 and 22 are then completed.

15 The magnetron is arranged for the direct radiation of high frequency energy through the walls of the envelope.

20 In one magnetron manufactured as described above, the following dimensions of the various parts were found suitable for operation at a wave length of 3 centimetres, the valve operating in the π -mode on the first space harmonic.

	Millimetres
Length of anode plate 5 along axis of envelope	13.1
Width of anode plate 5	12.7
Thickness of anode plate 5	2.5
Diameter of electron orbit space 9	2.0
Radial length of segments 11	8.0
Circumferential width of segments 11	1
30 Diameter of cathode 12	0.63
Diameter of choke cup 6	15
Axial length of choke cup 6	8
Diameter of envelope 1	119

¹ Outside.

35 With a magnetic field of 2000 gauss applied in the direction of the axis of the electron orbit space 9, the anode/cathode voltage required for operation on the first space harmonic was found to be 600 volts, and with an anode/cathode current of 10 millamps, the output of the device so operated was found to be about 100 milliwatts.

40 Such a magnetron is suitable for direct insertion along the axis of a circular waveguide of diameter 20 millimetres for the excitation of oscillations in the H_{10} mode in the waveguide by magnetic coupling with the loop formed by the parts of the anode plate bounding the resonator 10 furthest from the choke cup 6.

45 It will be appreciated that minor modifications of the construction just described may readily be made without appreciably affecting its suitability for operation on a space harmonic; for example the system of resonators 10 could be rotated through 45° and a short coupling probe provided on the anode segment furthest from the choke cup 6, said probe extending perpendicular to the plane of the anode plate.

50 In the second embodiment of the invention the construction of the magnetron is the same as that shown in Figures 1 and 2 except that the anode plate 5 is replaced by the anode plate 25 shown in Figure 3, which represents a view of one of the major faces of the plate.

55 The plate 25 is substantially rectangular and is pierced by an aperture whose periphery provides a central electron orbit space 26 and two resonator spaces each of which has the shape of a segment of a circle 27 communicating with the electron orbit space 26 through a parallel-sided slot 28 extending perpendicularly from the centre of the chord of the segment, said chords being parallel to each other. It is important that the sides of the slots 28 should be flat and not lost by roundings of the corners at the ends of the slots, although for increasing the L/C ratio in some cases the corners of the slots where they intersect the chords may be cut off by planes extending perpendicular to the major faces of the plate, for example at an angle of 45° to the chords.

60 In one magnetron having an anode plate of the kind shown in Figure 3 and otherwise constructed as described

with reference to Figures 1 and 2, the plate 25 being mounted on the choke cups with the anode segments 29 (formed between the two resonators 27, 28) parallel to the base of the choke cup, the following dimensions of the anode plate were found suitable for operation at a wavelength of 3 centimetres, the valve operating in the π -mode on the second space harmonic ($k=5$).

Millimetres

Length of anode plate 25 along axis of envelope	13.0
Width of anode plate 25	12.7
Thickness of anode plate	2.5
Diameter of electron orbit space 26	2
Radial length of slots 28	0.5
Width of slots 28	0.5
Radius of curvature of segments 27	3.7
Length of chords of segments 27	6.5
Diameter of cathode	0.6
Diameter of choke cup	15
Axial length of choke cup	8
Diameter of envelope	19

* Outside.

With a magnetic field of 2500 gauss applied in the direction of the axis of the electron orbit space 9, the anode/cathode voltage required for operation on the second space harmonic was found to be 900 volts, and with an anode/cathode current of 6 milliamps, the output of the device so operated was found to be about 500 milliwatts.

With the orientation of the resonators shown in Figure 3, a magnetron as just described is suitable for magnetic coupling with a load waveguide on either side of the anode, along the line of symmetry of the resonators; it will, however, be appreciated that the arrangement of resonators could readily be rotated through 90° to provide for magnetic coupling with a waveguide along the axis of the envelope.

In a modified form (not illustrated) of the magnetrons described with reference to Figures 1, 2 and 3, for obtaining greater rigidity of the electrode system the T-shaped supporting strip 8 is replaced by a hollow tube of non-magnetic material, such as a copper-nickel alloy, flanged at one end where it is screwed to the inside of the base of the choke cup 6 and the anode plate 5, and secured to the four support wires 4 at its other end, which end is open or perforated to permit evacuation and degassing during the pumping of the device; in addition a mica sheet is sandwiched between the base of the cup 6 and the anode plate 5, the edges of the sheet extending into abutment with the inner surface of the glass envelope 1; the mica sheet is cut away where the anode plate 5 is screwed to the choke cup 6, and the base of the anode plate extends at these regions into abutment with the choke cup to permit good thermal and electrical contact between the anode plate and choke cup; in addition the lead wires 20 and 22 pass through holes in the mica sheet, which serves also as an insulator replacing the ceramic bushings 21 and 23. A second mica sheet for supporting the free end of the anode plate from the envelope may also be provided in some cases.

Figures 4 and 5 illustrate schematically the way in which a magnetron of the form described with reference to Figure 3 may be utilised; in both figures the magnetron is represented only by the anode plate 25 and choke cup 6 within its envelope 1, the magnetron being shown fitted coaxially within a circular waveguide 30. In Figure 4 the face of the anode plate is shown and in Figure 5 an end of the anode plate is shown; in both figures magnetic coupling between the resonator remote from the choke cup and the waveguide is indicated by the dotted lines 31, and the transmission of energy along the waveguide is in the direction of the arrow 32.

The strength of the coupling of the magnetron to the waveguide may be controlled, in the design of the device,

by variation of the dimensions marked x and ea , reduction of either, or both, increasing the coupling.

Figure 6 illustrates in a similar way a modification of the magnetron described with reference to Figure 3, arranged for the excitation of a rectangular section waveguide; the modification consists of the rotation of the anode system through 90°, and of the addition of a second choke cup 33 at the opposite side of the anode of the choke cup 6 (in other modifications the choke cup 33 may be omitted). The waveguide system consists of a rectangular section waveguide intersected at right angles by a circular section waveguide 34, so as to leave on one side of the circular waveguide an open end rectangular section stub 35, the other rectangular section branch 36 providing the load coupling waveguide. The magnetron 37 is inserted coaxially along the circular section waveguide so that its anode system lies at the intersection of the two waveguides; coupling takes place from each resonator of the anode system to the rectangular waveguide sections 35 and 36; in the stub 35 is fitted a tuning plunger 38, and the output energy of the magnetron is arranged to be transmitted along the branch 36 in the direction of the arrow 39 to a load represented by the rectangle 40, which may, for example, be a mixer unit in a radio or radar receiver.

By adjustment of the plunger 38 the reactive load on the anode system of the magnetron 37 can be varied and its frequency of oscillation controlled over an appreciable range.

It will be appreciated that whilst in a magnetron in accordance with the invention the anode must be generally of plate form, the major faces need not everywhere be parallel, and in particular the shape of the anode segments may be varied for enabling the electrical constants of the anode system, such as the L/C ratio of the resonators, to be varied, for example for adjustment of the tuning range or for control of the output coupling. Thus Figures 7 and 8 illustrate two such modifications in a magnetron of the kind shown in Figure 6, having only a single choke cup.

Each of Figures 7 and 8 shows a section through the anode plate 41 mounted on a choke cup 42, the section being taken in a plane perpendicular to the major faces of the plate through the centres of the anode segments. In Figure 7 the thickness of each of the segments 43 tapers from the electron orbit space to the edge of the plate, whilst in Figure 8 the length of the anode at the electric orbit space is effectively increased by the addition of lips 46 at the end of the segments 45.

It may be observed that whilst the magnetrons in accordance with the invention have been described relative to their operation in the π -mode, for which they are particularly designed, it will in general be possible for them to be operated in other modes, and this may sometimes be desirable for obtaining different output frequencies.

We claim:

1. A travelling wave magnetron oscillator suitable for operation on a space harmonic of the π -mode of oscillation of the anode resonator system, having a sealed evacuated envelope which is at least partly of insulating material and contains an anode in the form of a metal plate pierced perpendicular to its end faces by an aperture whose perimeter provides a cylindrical inner space which forms the electron orbit space, and an even plurality, not exceeding six, of spaces which form similar cavity resonators extending radially from the electron orbit space and arranged around its axis in harmonic positions, having a cylindrical cathode mounted coaxially within the electron orbit space, and having leads to the anode and cathode extending through the sealed envelope, the anode plate aperture being dimensioned to produce a π -mode resonant frequency corresponding to a free-space wavelength λ with the diameter of the electron orbit space being not greater than $\lambda/10$ and its axial length being

11

not greater than $3\lambda/10$, and wherein at least a free edge part of the anode plate about a line of symmetry of one of the cavity resonators is positioned so close to an insulating material part of the envelope that the electromagnetic field linked with said edge part will pass directly through said insulating material part for the output coupling of the magnetron to a load waveguide.

2. A travelling wave magnetron oscillator according to claim 1, wherein the axial length of the electron orbit space is also not greater than $\lambda/10$.

3. A travelling wave magnetron oscillator according to claim 1 designed specifically for continuous wave operation and wherein the ratio of cathode diameter to the diameter of the electron orbit space is about 0.3.

4. A travelling wave magnetron oscillator according to claim 1, wherein the anode cavity resonators are arranged symmetrically around the axis of the electron orbit space.

5. A travelling wave magnetron oscillator according to claim 1, wherein the angular width of the mouth of the cavity resonators exceeds $\pi/2k$ radians but is different from $2\pi/k$ radians, where k is the value of $Np/2$ corresponding to the operating space harmonic, N being the number of cavity resonators and p being a small integer.

6. A travelling wave magnetron oscillator according to claim 1, wherein the anode plate is mounted on the base of a cylindrical choke cup within a coaxially cylindrical glass envelope, the sides of the choke cup extending away from the anode, being of axial length electrically equivalent to $\lambda/4$, and approaching close to the inner surface of the envelope so as to form a quarter wavelength choke when the envelope is inserted in a closely fitting waveguide.

7. A travelling wave magnetron oscillator according to claim 1, having four cavity resonators defining between themselves four rectangular anode segments, each of which segments extends radially from the surface of the electron orbit space with the segments symmetrically arranged around the space.

8. A travelling wave magnetron oscillator according to claim 1, having two cavity resonators each in the shape of a segment of a circle communicating with the electron orbit space through a slot extending perpendicular to and from the centre of the chord of the segment, said chords being parallel to each other.

9. A travelling wave magnetron oscillator according to claim 8, wherein each of the said slots is parallel-sided near the electron orbit space and then flares outwards, with straight sides, to the segmental part of the resonator.

10. A travelling wave magnetron oscillator according to claim 8, wherein the anode plate is mounted on the base of a cylindrical choke cup within a coaxially cylindrical glass envelope with the chords of the segmental parts of the cavity resonators parallel to the base of the choke cup, the sides of the choke cup extending away from the anode and being of axial length electrically equivalent to $\lambda/4$, and wherein the curved side of the segmental part of the cavity resonator further from the choke cup extends so close to the edge of the plate that said edge part of the plate constitutes in effect an output

loop the electromagnetic field linked with which extends to the exterior of the envelope.

11. A travelling wave magnetron oscillator according to claim 8, wherein the anode plate is mounted between two coaxial cylindrical choke cups within a coaxially cylindrical glass envelope, each choke cup extending away from the anode and being of axial length electrically equivalent to $\lambda/4$, wherein the chords of the segmental parts of the cavity resonators extend parallel to the axes of said choke cups and the curved side of each said segmental part extends so close to the edge of the anode plate that said edge part of the plate constitutes in effect an output loop the electromagnetic field linked with which extends to the exterior of the envelope.

12. A travelling wave magnetron oscillator according to claim 8, wherein the thickness of the anode segments between the cavity resonators tapers from the sides of the electron orbit space towards the edge of the plate.

13. A traveling wave magnetron oscillator according to claim 8, wherein the axial length of the anode at the electron orbit space is increased by lips extending coaxial with the electron orbit space from the inner end of the anode segments.

14. The combination of a travelling wave magnetron according to claim 5 with a waveguide, wherein the cylindrical glass envelope is positioned coaxially within a closely fitting cylindrical waveguide so that output energy from the magnetron can excite oscillations in the waveguide.

15. The combination of a travelling wave magnetron oscillator according to claim 11 with crossed cylindrical waveguides wherein the cylindrical envelope of the magnetron is positioned coaxially within a first one of said waveguides so that the anode lies at the intersection of the waveguides with each branch of said first waveguide extending from the intersection electrically closed by one of the magnetron choke cups, a load connected to one of the branches of the second waveguide for receiving oscillations excited in said branch by the magnetron, and a plunger closing the other branch of said second waveguide, the position of which plunger is adjustable for controlling the output frequency of the magnetron.
